R. T. WITHERS
DEVICE FOR ERECTING SECTIONAL STEAM OR HOT
WATER CAST IRON BOILERS OR THE LIKE
Filed July 1, 1924

UNITED STATES PATENT OFFICE.

ROBERT T. WITHERS, OF NEW CASTLE, PENNSYLVANIA.

DEVICE FOR ERECTING SECTIONAL STEAM OR HOT-WATER CAST-IRON BOILERS OR THE LIKE.

Application filed July 1, 1924. Serial No. 723,608.

To all whom it may concern:

Be it known that I, ROBERT T. WITHERS, a citizen of the United States, residing at New Castle, in the county of Lawrence and State of Pennsylvania, have invented certain new and useful Improvements in Devices for Erecting Sectional Steam or Hot-Water Cast-Iron Boilers or the like, of which the following is a specification, reference being had therein to the accompanying drawing.

This invention relates to devices for erecting sectional steam or hot water cast iron boilers or the like, the device being more specifically a slotted rod adapted to receive a wedge for forcing the boiler sections into their assembled positions.

It is the usual practice for boiler manufacturers to furnish, as part of a boiler, rods upon which the boiler sections are erected. Ordinarily these rods are provided at one end with an enlarged head and are additionally provided with a collar having set screws for forcing the boiler sections together. In assembling boiler sections with these devices the work is slow and tedious the method being a cumbersome one as after each boiler section is set in place it is necessary to put on the collar with the set screws and tighten the enlarged head down to draw the sections together. It is then necessary to loosen the set screws in the collar and remove the same thereafter placing another boiler section in place and repeating the before-mentioned operation.

In erecting boilers the sections are given a water-tight connection through the use of short tubes called push-nipples which provide a connection between the interiors of the several sections. The sections are then pushed or forced together over the push nipples squeezing these nipples into the apertures in the boiler sections thus providing a steam and water-tight joint between the sections.

Having in mind the slow and cumbersome methods now used in erecting sectional boilers, I have invented the device hereinafter described and set forth in the accompanying drawings and specification.

One of the objects of my invention is to provide a device of simple construction

which is adapted for use in assembling the sections of boilers, radiators or the like.

Another object of my invention is to provide a novel construction of rod and wedge for assembling sectional boilers, radiators or the like.

A still further object of my invention is to provide a device for the purpose described which is cheap and simple of manufacture and highly efficient in operation.

Other further objects novel features of construction and improved results of my invention will appear in the following description and accompanying drawings.

In the drawings: Figure 1 is a view in elevation showing the manner of erecting the boiler, three of the sections having been assembled.

Fig. 2 is a view in vertical section showing the manner of using and applying my invention.

Fig. 3 is an enlarged detailed view showing the wedge receiving opening of the rod.

Fig. 4 is a detailed view showing the wedge inserted through the rod opening.

Referring to the several parts which constitute my invention as shown in the accompanying drawings, 5, 6 and 7 represent the several sections of a boiler or radiator. It will of course be readily understood that the heating device can be constituted of as many sections as is desirable or as is necessary to accomplish the desired result. In the case of boilers the same are supported on a suitable base 8 which is common to constructions of this character.

Sectional boilers or radiators are furnished with tie or assembling rods at both their upper and lower ends. I have designated these rods by the numeral 9.

The rods which I have provided however are of a particular construction. These rods 9 are screw-threaded at their ends to receive the nuts 10 which carry in front of them the enlarged washers 11 or the like. These rods are provided of course of a length to assemble a specified number of sections. The rods shown in Fig. 1 are for assembling a boiler having eight parts.

At a plurality of points intermediate the rods they are provided with openings 12 which are spaced apart a width equal to

the width or thickness of the boiler sections. One wall of these openings 12 is tapered as designated at 13 so that the openings are of a size and shape to receive the wedge 5 shaped pins or keys 14.

Referring now again to the boiler sections it will be seen that these sections are provided with apertures 15 adjacent both their upper and lower ends. In the assembled 10 boiler the contacting apertures of the sections are joined together by the push nipples 16 so as to make a water or steam tight joint between the sections.

In assembling the sections the nuts 10 and 15 washers 11 are removed from one end of the rods and one of the boiler sections is placed on the base 8. The rods are then inserted through the apertures in the upper and lower ends of this section so that the 20 washers 11 of the rods abut the outer face of this section and prevents the rod from being pulled inwardly through the opening 17 of the section, as clearly appears in Fig. 2 of the drawing.

25 Before the next section is placed the push nipples 16 are inserted in the aperture 16 of the section. It will be seen that one half of the nipple extends outwardly beyond the opening. In placing the next section it is necessary to force this outstanding portion 30 of the nipple into the aperture of the section so that the faces of the two sections will abut.

This is accomplished by the use of the 35 wedge or key 14. The wedge is placed in the tapered opening 13 of the rod behind the section which it is desired to force over the nipple. By driving the wedge into the rod opening 13 the boiler section will be pushed forward over the push nipple until this section face firmly abuts the face of the first section which has been put in place.

40 To erect the entire boiler it is only required to repeat the operation which is described.

45 It will be readily understood of course that as each section is forced into place the wedge will be removed and used in forcing the next section into its proper position. 50 The last section to be assembled is forced into place by the use of the nuts 10 and washers 11 at the extreme end of the tie or assembly rods 9.

55 If it is desired the rods may be withdrawn after the assembling of the boiler has been completed and a set of solid rods substituted in their place. By substituting the solid rods my improved slotted rods could then be used for assembling another boiler. 60 However if desired my slotted rods can be used as the permanent tie rods of the boiler or radiator. In many instances my rods would probably be used as the permanent tie rods as their cost is not much greater 65 than the cost of the ordinary solid rod and

the saving in time by leaving them in as the permanent rods would probably offset the small saving accomplished by removing them and using them again when assembling another boiler.

70 In other instances it would be necessary to use my rods as the permanent tie rods as the boiler or furnace room in which the furnace is erected would not be large enough to permit the rods to be withdrawn once the 75 boiler had been erected. As my improved rods would be the proper length of the completely erected boiler this of course would be permissible and the rods would be finished off at their outer ends with the usual 80 bolts 10 and washers 11, before mentioned. The operation heretofore described can if desired be reversed to a certain extent. If desired after the first boiler section is in place the nuts 10 and washers 11 are removed from the end of the rods and the 85 wedge or key 14 inserted in the second aperture in the rod. The second boiler section is then placed on the base and the rod inserted through the two sections. To draw the second section into place it is only necessary to again place the washers 11 and nuts 10 on the ends of the rods and tighten down the nuts 10 until the second section is drawn 90 into place. A slight tap with a hammer or the like on the small end of the key will then release the pressure of the nuts 10 so that they can be backed off by hand and the rod removed from the sections so that the 95 third section can be placed upon the base 100 and drawn up into place in the manner described in respect to the second boiler section.

105 From the foregoing it will be seen that I have provided a device by which sectional boilers or radiators can be much more rapidly and easily assembled than has been done heretofore. It will also be seen that the cost of my assembling device is very cheap, so cheap in fact that if desired my 110 slotted rod can be used as the permanent tie rod for the completed boiler or radiator.

115 Having thus described my invention what I claim and desire to secure by Letters Patent is:

1. A device for assembling a sectional boiler or the like, comprising a tie rod adapted to be passed through said sections, said tie rod carrying means intermediate the length of the tie-rod for forcing the 120 sections together.

2. A device for assembling a sectional boiler or the like, comprising a tie rod adapted to be passed through said sections, the tie rod provided with tapered openings, and wedge-shaped members adapted for insertion in said tie-rod openings for forcing the sections together.

125 3. A device for assembling a sectional boiler or the like, comprising a tie rod 130

- adapted to be passed through said sections, said tie rod provided with tapered openings, said openings positioned at a plurality of points intermediate the length of the rod 5 and spaced apart a distance equal to the thickness of the boiler sections, and wedge-shaped members adapted for insertion in said tie rod openings for forcing the sections together.
- 10 4. A device for assembling a sectional boiler or the like, comprising a tie rod adapted to be passed through said sections, said tie rod carrying means intermediate the length of the tie rod for forcing the sections together, and said intermediate means comprising wedge-shaped members.
- 15 5. A device for assembling boiler sections, comprising a rod threaded at one end, a clamping nut on said threaded end, a movable abutment adjustable along said rod, and said movable abutment comprising a pin.
- 20 6. A device for assembling boiler sections, comprising a rod threaded at one end, a
- clamping nut on said threaded end, the rod 25 provided with a plurality of tapered openings intermediate its length, and wedge-shaped members adapted for insertion in said openings, for the purpose described.
7. A device for assembling boiler sections, 30 comprising a rod threaded at its ends, nuts on said threaded ends, the rod provided with openings intermediate its ends, and a wedge abutment adapted for insertion in said openings, for the purpose described. 35
8. An assembling or tie rod for boilers or the like, having its ends threaded, clamping nuts on said threaded ends, said rod provided with tapered openings intermediate its length, and said openings positioned a 40 distance apart equal to the thickness of the boiler sections, and wedge-shaped members adapted for insertion in said openings, for the purpose described.

In testimony whereof I hereunto affix my 45 signature.

ROBERT T. WITHERS.
